UNITED STATES PATENT OFFICE.

JOHN M. JOHNSON, OF CHICAGO, AND WILLIAM G. GOTTSCHALL, DECEASED, LATE OF CHICAGO, ILLINOIS, BY HENRIETTA H. GOTTSCHALL, ADMINISTRATRIX, OF CHICAGO, ILLINOIS, ASSIGNORS TO HART, SCHAFFNER & MARX, OF CHICAGO, ILLINOIS, A CORPORATION OF ILLINOIS.

CLOTH-TREATING MACHINE.

1,410,256.

Specification of Letters Patent. Patented Mar. 21, 1922.

Application filed May 13, 1921. Serial No. 469,153.

To all whom it may concern:

Be it known that JOHN M. JOHNSON, a citizen of the United States, residing at Chicago, Cook County, Illinois, and WILLIAM G. GOTTSCHALL, deceased, late a citizen of the United States, and a resident of Chicago, Cook County, Illinois, the administratrix of the estate of said WILLIAM G. GOTTSCHALL being HENRIETTA H. GOTTSCHALL, a citizen of the United States, and a resident of Chicago, Cook County, Illinois, did prior to the decease of said WILLIAM G. GOTTSCHALL jointly invent a certain new and useful Improvement in Cloth-Treating Machines, of which the following is a specification.

This invention relates to cloth treating machines, the purpose whereof is to take the cloth as it comes from the mill and prepare it for tailoring. It will be understood by those skilled in the art that cloth, especially woolen fabric, as it comes from the mill has a "mill finish" which leaves the fabric in a glossy condition and this finish should be dulled before the cloth is cut and fashioned into garments. Furthermore, the cloth as it comes from the mill is shrinkable and must be shrunk before it can be properly made into clothing. The purpose of this invention is to provide organized mechanism which will remove the mill finish and shrink the cloth in a continuous and uniform manner.

The object of the invention is obtained by the mechanism illustrated in the accompanying drawings in which—

Figure 1 is a side elevation of the complete machine, and

Figure 2 is a longitudinally sectional elevation thereof.

Like numerals denote like parts in the two views.

Referring to the drawings, a "steamer" is provided which in the type illustrated consists of a U-shaped receptacle 1 with a screen 2 stretched across the top, said screen being covered by a sheet 3 of loosely woven fabric designed to distribute and diffuse the steam rising from the receptacle. Steam is supplied to the receptacle by a pipe 4 which has a horizontal portion 6 located within the receptacle and perforated at the top for the exit of steam. By preference, this horizontal portion of the pipe is surrounded by

an outer sheet 7 which is perforated at frequent intervals along the bottom, thus tending to distribute the steam within the receptacle. 55

The cloth is usually treated a bolt at a time, the bolt thus affording a long strip of cloth which may be passed continuously through the machine. This strip is indicated in general by the reference numeral 9 and is usually carried upon a truck 10 which in practice is rolled to the head end of the machine as illustrated. From the truck the cloth passes around suitable guide rollers. In the present case a roller 12 is provided at the top of a frame 13 and a second roller 14 is arranged at a lower part on the frame. On either side of the steamer are guide rollers 16, 17. These are so placed as to receive the cloth from the roller 14 and to guide the cloth horizontally over the top of the steamer in close proximity to it. The cloth is thus subjected to the action of the steam rising from the steamer. 70

Adjacent to the steamer is a water bath which consists chiefly of a tank 20. A guide roller 22 is mounted near the bottom of the tank near the head end thereof, and the cloth passes from roller 17 under roller 22 and thence over the first of a pair of squeezers 23, 24. These squeezers are preferably "semi-vulcanized" rubber, the material being soft enough, however, to be somewhat yielding. The cloth passes between these two squeezers and down to a guide roller 26 near the bottom of the tank at the rear end thereof. At the rear end of the tank are two uprights 30 which support wringer rolls 32. 80 These are geared together so as to rotate in synchronism and one of them is driven by a pulley 33 or other suitable power device. In the form illustrated the pulley is driven by a belt 34 from a drive pulley 35. 85

From the wringer the cloth passes to an overhead guide and traction roller 40 mounted on a shaft 42 journaled in a framework 43. The cloth passes thence to two rollers 44, 46 of a plaiting or piling machine 100 adapted to deposit the cloth in a pile 50 on a truck 51 or other suitable receiver. Roller 44 is journaled at the free end of arms 52 which are suspended from a shaft 54 mounted in stationary frame 43. Roller 46 105 is journaled at the free end of arms 56

which are suspended from pivots 57 carried by the arms 52 of the rocking frame. The two rollers are constantly urged toward each other by tension springs 60.

5 The rocking frame is oscillated about shaft 54 by any suitable mechanism. In the present case there is a crank 62 rigidly fastened to a shaft 64 journaled in frame 43. Said crank is connected to arms 52 by connecting rods 66. The result is that as the crank rotates the frame is rocked back and forth and piles the cloth upon the truck.

The rollers 40 and 44 are power driven and while the gearing may in many respects be varied, it has been contrived to drive them in synchronism by chain gearing. In the form shown, the lower wringer shaft is provided with a sprocket 70 which drives a chain 71 which passes over a suitable 15 sprocket fastened to shaft 64. Said shaft has fastened to it a sprocket 74 which drives a chain 76 which passes around a sprocket 78 fastened to shaft 42. Shaft 64 also has fastened to it a sprocket 72 which drives a 20 chain 80 which passes around a sprocket 81 fastened to shaft 54. A second sprocket 82 is fastened to shaft 54 and drives a chain 84 which passes around a sprocket 86 fastened to the shaft 90 to which roller 44 is attached. 25

30 As the sprockets 81 and 82 are concentric, it follows that the shaft 90 will be rotated even though the shaft also has a vibratory movement due to the oscillation of the rocking frame.

35 The operation of the machine will now be readily understood. The cloth is brought to the machine on a truck or other support and threaded through the machine as follows: Over the roller 12, under roller 14, 40 thence to rollers 16 and 17 by which the cloth is subjected to the action of the steamer. Thence the cloth passes under the roller 22 which is submerged in the water tank. The cloth then proceeds to and passes 45 between the squeeze rollers 23, 24, after which it again descends into the water, passing under the guide roller 26. From roller 26 it rises to and passes between the wringer rolls 32, after which it travels over the stationary guide and traction roller 40. From roller 40 it passes through the plaiting machine which in vibrating backward and forward, piles the cloth upon the truck 51 or other suitable receiver. The rollers 40 and 50 55 and the wringer rollers 32 are all power driven and hence tend to draw the cloth along the path described. The consequence is that as the cloth is drawn from the pile on truck 10 it passes through the machine 60 and is finally deposited in the pile 50. The effect of the steamer is to soften and shrink the fibers of the fabric and prepare it to absorb water, and it has been found in practice that the steamer alone will sometimes 65 produce a shrinkage of ten per cent in the

width of the strip. The cloth passing from the steamer down into the water bath becomes saturated with water and the effect of the squeeze rollers 23, 24 is not only to wring a considerable portion of the water 70 from the cloth, but to further soften the fibers and promote the shrinking effect. When wool fibers are examined under the microscope they are seen to have small scales which tend to interlock when the fibers are 75 rubbed together, especially if wet, and this not only strengthens the fabric, but also shrinks and softens it. As the cloth leaves the squeezer rollers it again passes into the bath and thence to the wringer, the latter 80 removing the surplus water and still further softening the fabric. From the wringer the cloth passes to the piling machine which deposits the cloth in layers as illustrated. In practice the cloth is permitted thus to remain piled for a considerable period. This produces "sweating" or heating, due to the weight of the fabric itself and to the heating action of the oil contained in the fabric. After the sweating process has continued 85 for a suitable time the cloth is dried and ready for use in the production of garments.

It will be evident from the foregoing description and a reference to the drawings that the machine is continuous in its operation, taking the cloth from the bolt or pile and subjecting it to the sequence of steps from steaming to piling. As the various parts of the machine are positively geared together, they are certain to operate in synchronism and thus avoid any tendency to unduly stretch the cloth or to permit one portion to gain on another and thus accumulate within the apparatus itself. Furthermore, the effect of the process is uniform 90 throughout the entire length of the piece.

Having thus described our invention, what we claim as new and desire to secure by Letters Patent is:

1. Organized mechanism for treating cloth 110 having a steamer, a water bath, a wringer, and means for causing the cloth to travel first through the zone of action of the steamer, then into and through the water bath and thence through the wringer. 115

2. A cloth treating machine having an open top vessel, a substantially horizontal screen at the top of said vessel for supporting the cloth and subjecting it to the action of the steam rising from the vessel, means 120 for supplying steam to said vessel, a water bath, a wringer, and means for drawing the cloth continuously across the top of said screen, thence into and through the bath and thence through the wringer. 125

3. In a cloth treating machine, the combination of a steamer comprising a vessel open at the top and provided with foraminous material for diffusing the steam rising from said vessel, a water bath, a wringer, 130

cloth piling means, and means for continuously and uniformly feeding the cloth through the zone of action of the steamer, thence through the bath, thence through the 5 wringer, and thence through the piling machine.

4. In a cloth treating machine, the combination of a steamer comprising a vessel open at the top and provided with foraminous 10 material for diffusing the steam rising from said vessel, a water bath, a wringer, cloth piling means, tractive means for drawing the cloth from the wringer to the piling mechanism, tractive means for causing the 15 cloth to travel through the piling mechanism, and means for driving the said two tractive means in synchronism.

5. In a machine of the class described, the combination of a piling machine adapted to 20 oscillate about a horizontal pivot, tractive means for feeding the cloth through said piling mechanism, a wringer, means for feeding the cloth from the wringer to the piling machine, a steamer, and a water bath, the 25 wringer being adapted to draw the cloth past the steamer and through the water bath, and the wringer and tractive means having mechanism for driving them always at the same speed ratio.

30 6. In a machine of the class described, the

combination of an oscillatory frame, a feed roller at the free end of said frame for leading the cloth backward and forward in a horizontal direction to pile it, means for wetting the cloth, tractive means for drawing the cloth from the wetting means to the piling machine, and means for synchronizing the feed roller and tractive means. 35

7. In a machine of the class described, the combination of an oscillatory frame, a feed 40 roller at the free end of said frame for leading the cloth backward and forward in a horizontal direction to pile it, means for wetting the cloth, tractive means for drawing the cloth from the wetting means to the 45 piling machine, and means for synchronizing the feed roller and tractive means, a portion of the synchronizing means being concentric with the axis of the oscillatory frame. 50

In witness whereof, we, JOHN M. JOHNSON and HENRIETTA H. GOTTSCHALL as administratrix of the estate of WILLIAM G. GOTTSCHALL, deceased, have hereunto subscribed our names.

JOHN M. JOHNSON.

HENRIETTA H. GOTTSCHALL,

*Administratrix of William G. Gottschall,
deceased.*
